[57] CLAIM

The ornamental design for an endometric brush, as
shown and described.

DESCRIPTION

FIG. 1 is a top plan view of an endometric brush, showing
my new design, with the brush in a sample collecting
position;

FIG. 2 is a side elevational view thereof;

FIG. 3 is a side elevational view thereof, rotated 90
degrees in relation to FIG. 2;

FIG. 4 is a top plan view thereof, with the brush in
partially retracted position;

FIG. 5 is a side elevational view thereof; and

FIG. 6 is a side elevational view thereof, rotated 90
degrees in relation to FIG. 5.

FIG. 2
